UNITED STATES PATENT OFFICE.

ROBERT N. STOCKTON, OF PHILADELPHIA, PENNSYLVANIA.

FISHING-GIG.

SPECIFICATION forming part of Letters Patent No. 326,803, dated September 22, 1885.

Application filed April 28, 1885. (No model.)

To all whom it may concern:

Be it known that I, ROBERT N. STOCKTON, of Philadelphia, in the county of Philadelphia and State of Pennsylvania, have invented a new and valuable Improvement in Fishing-Gigs; and I do hereby declare that the following is a full, clear, and exact description of the construction and operation of the same, reference being had to the annexed drawings, to making a part of this specification, and to the letters and figures of reference marked thereon.

Figure 1 is an elevation of the spear-head, showing the movable jaws opened and closed; and Fig. 2 is an enlarged broken detail section.

My invention has relation to fishing-spears or analogous devices having pivoted spring-acting jaws; and it has for its object to provide an inexpensive, simple, effective, and quickly-acting spear.

My invention accordingly consists of the combination, construction, and arrangement of parts as hereinafter particularly described and claimed.

In the drawings, A represents the spear rod or handle, having a T-shaped end or head, a, to the ends of the horizontal bar a' of which are pivoted angular-shaped arms B. The ends b of arms B have on their adjacent sides series of fixed claws, splines, or points b', and these ends form the jaws between which the fish or object is caught. The ends b² of arms B are adjacent to spear-rod A, and are in con-

tact with and acted upon to close said jaws 35 together by suitable flat or other springs, C, secured to the spear-rod.

One of the arms B is provided with a lateral opening, d, through which passes the end e of a trigger-bar, E, which end has a spring, 40 e², attached thereto by a band or ferrule, e', and retaining-stud e³, while the other end of said trigger has a recess or shoulder, e⁴, for engagement with the remaining arm B to hold said arms open or apart, as indicated in 45 full lines, Fig. 1. When in this position, the least contact of an object—as, for instance, a fish swimming between the jaws b b—with the trigger-bar E causes its spring e² to act to set it off or disengage itself from locked arm B, 50 whereupon the arms are suddenly closed together by springs C to catch such object or fish.

What I claim is—

A fishing-spear having T-head a, bent arms 55 B B, having ends b, with fixed inside claws, b', and ends b², springs C, and opening d in one of the arms B, and a trigger, E, having spring e², and end e, passing through arm-opening d, and a recessed end, e⁴, substantially as shown and described.

In testimony that I claim the above I have hereunto subscribed my name in the presence of two witnesses.

ROBERT N. STOCKTON.
